Fidelis M. Morgan, Chula Vista, Calif. (Bancroft Palms
Mobile Park 26, 3221 Bancroft Drive, Spring Valley,
Calif. 92077)

Filed Apr. 4, 1973, Ser. No. 348,295

Term of patent 14 years

Int. Cl. D2—02

U.S. Cl. D2—187

FIG. 1.

FIG. 2.

FIG. 1 is a front elevational view of a jacket showing my new design; and

FIG. 2 is a rear elevational view thereof.

The characteristic feature of my design resides in the combination on a jacket of a rolled collar, a fringed bottom edge, and fringed edged sleeves, all as shown on the drawing.

I claim:

The ornamental design for a jacket, as shown.
